Attorney.

UNITED STATES PATENT OFFICE.

FULGENCIO ARCHILA, OF BOGOTA, COLOMBIA.

ELECTRIC SIGN.

Application filed April 3, 1924. Serial No. 703,991.

The present invention relates to electric switches, and the invention aims to provide a novel and improved circuit controller for controlling the circuits of electric lamps or other elements energized by electricity.

Another object is the provision of such a controller for electric circuits which can be operated by the finger or any suitable implement in order that the circuits can be closed momentarily or may remain closed for a period of time, depending on the amount of depression of the keys or buttons which control the switches of the circuits. Thus, by pressing on the buttons or keys lightly, the circuits are only closed as long as the light pressure is applied, and by moving the finger or implement about over the buttons or keys, the different circuits may be closed corresponding to the line of movement of the finger or implement. By depressing the keys or buttons further they are held to keep the corresponding circuits closed.

A further object is the provision of novel means for restoring the keys or buttons and opening the switches in groups or zones or in toto.

With the foregoing and other objects in view, which will be apparent as the description proceeds, the invention resides in the construction and arrangement of parts as hereinafter described and claimed, it being understood that changes can be made within the scope of what is claimed, without departing from the spirit of the invention.

The invention is illustrated in the accompanying drawings, wherein—

Fig. 1 is a diagrammatical view showing the electrical circuits.

Fig. 2 is a fragmentary plan view of the controller.

Fig. 3 is a fragmentary side elevation of the controller, portions being broken away and portions shown in section.

Fig. 4 is another fragmentary elevation of the controller.

As shown there is a group of electric lamps or other elements 13 which may comprise an electric sign and each lamp 13 is connected by a common conductor 17 through an electric generator 18 or other source of electrical energy and a rheostat 19 for controlling the current with the controller switches 20, and individual conduc-

tors or wires 21 extend from the lamps 13 to the corresponding switches 20 of the controller.

The controller may have its switches arranged in the same manner as the lamps 13. The controller comprises a suitable frame or case 22 of wood or other insulating material, and the conductors or wires 17 and 21 preferably extend from the lamps 13 to the controller in a cable 23. Mounted in the frame or case 22 are the superposed metal plates 25 and 26 to which the conductor 17 is connected.

The switches 20 of the controller comprise plungers 27 slideable vertically through the plates 25 and 26, so that all of said plungers are in electrical connection with the common conductor 17. Said plungers have buttons or keys 28 at their upper ends distributed over the face of the controller, and said buttons are of suitable insulating material. Springs 29 are confined between the plate 26 and shoulders 30 of the plungers for normally raising said plungers. Stops 31 are carried by the plungers 27 below the plate 26 to contact with said plate and limit the upward movement of the plungers.

The switches include, as their other contacting parts, upstanding tubular sockets 32 secured in the bottom portion of the frame or case 22, and the upper portions of the sockets are slotted, as at 33, so as to be capable of expanding to receive the knobs or enlargements 34 at the lower ends of the plungers. The enlargements 34 are adapted to be moved down into the sockets, the upper terminal portions or mouths of the sockets being expandable to receive said enlargements. The sockets 32 are further provided with indentations 35 adjacent to their upper ends to snap over the enlargements 34 when the plungers are completely depressed to move the enlargements below the indentations 35. The plungers will be frictionally held in full depressed position when the enlargements 34 pass below the indentations 35, causing the sockets to contract over the enlargements. However, the plungers can be forcibly raised to withdraw the enlargements 34 from the sockets, as will presently appear.

The wires or conductors 21 leading to the lamps are connected to the corresponding sockets 32 of the controller, so that when a

plunger of the controller is depressed to contact with the corresponding socket 32, the corresponding lamp circuit is closed.

The plunger or switch restoring means of the controller comprises cam bars 36 parallel with one another and slidable in the frame or case 22 above the plate 25 and under the buttons or keys 28, said bars having cams 37 upstanding therefrom and normally located between the buttons, so as not to interfere with the depression of the buttons. However, when the bars are slid lengthwise, the cams will raise the buttons and plungers to open the switches.

In order that the lamps of several zones or sections of the sign can be extinguished, for changing the display or correcting errors, the cam bars 36 are connected in groups, each group having several bars 36 which are connected at one end by a cross rod 38 so that the bars of each group can be moved simultaneously for opening the switches of the corresponding zone or section of the controller, thereby extinguishing the lamps of the corresponding zone or section of the sign. This may be desirable when only a portion of the sign is to be changed, or when an error has been made in one portion of the sign, the lamps of such zone or section being readily extinguished to make the change or correction without extinguishing the lamps of the other zones.

The operating means for the cam bars 36 includes a lever 39 for each group of bars engaging, at one end, the cross rod 38, and fulcrumed between its ends in the frame or case 22. A core 40 is pivoted to the opposite end of the lever and works in a solenoid 41 which, when energized, attracts the core 40 to slide the bars 36 so as to raise the plungers 27 out of engagement from the sockets 32. A spring 42 is connected to each lever 39 for restoring the switch opening or clearing means to normal position when the solenoid is deenergized. Each solenoid or electro-magnet 41 is connected, as seen in Fig. 1, in series with the generator 18 and rheostat 19, and a switch 43 is included in the circuit of each solenoid for conveniently closing the solenoid circuits, when it is desired to clear a portion of the sign or the entire sign.

By pushing down on the buttons or keys 28, to force the enlargements 34 of the plunger into the sockets 32 under the indentations 35, the plungers are held down by the sockets, thereby holding closed the circuits of the corresponding lamps of the sign. The buttons can be depressed by the fingers or any suitable implement which can be moved over the area covered by the buttons or keys, so that letters, words, pictures, and other characters can be "written", "printed" or "drawn" on the sign.

The buttons can also be depressed by patterns and other devices for obtaining different illumination effects. When a button 28 is depressed lightly, without sufficient force to shove the plunger down into the socket, the plunger will be immediately raised by the spring 29 as soon as the pressure is relieved. Thus, by moving the finger or implement over the buttons, with a light touch, the switches can be closed momentarily, and the lamps of the sign will be lighted along the corresponding line, to give the effect of a moving point or dot. The button at the end of the line can be pushed down so as to be held by the corresponding socket, to keep the corresponding lamp lighted, and the operation can be repeated by moving the finger or implement in different directions over the board to "build up" the character to be displayed by dots or spots of light moving over the area of the sign and brought to predetermined positions in succession to complete the character step by step.

As described hereinbefore, different zones or sections of the sign can be cleared by pressing the switches 43, to energize the solenoids 41, so that the cam bars 36 are slid to forcibly raise those plungers 27 which are held by the sockets 32. Different zones or sections of the sign can be cleared, or the entire sign may be cleared.

Having thus described the invention, what is claimed as new is:

1. A controller comprising spring-retracted plungers, members for the frictional engagement of said plungers and arranged to frictionally hold the plungers in engagement therewith, and bars extending across said plungers and slidably longitudinally, said bars having individual cams to contact with the plungers, and the bars being so arranged with reference to the plungers that when the bars are slid longitudinally the cams thereof contact with the plungers and forcibly retract the plungers from said members.

2. A controller comprising rows of spring-retracted plungers, members for the frictional engagement of said plungers and arranged to frictionally hold said plungers in engagement therewith, bars mounted for longitudinal sliding movement between the rows of plungers and having individual cams to contact with the plungers, and the bars being so arranged with reference to the plungers that when the bars are slid longitudinally the cams thereof contact with the plungers and forcibly retract the plungers from said members, and means for sliding said bars longitudinally.

In testimony whereof I hereunto affix my signature.

FULGENCIO ARCHILA.
